G. H. BACKMIRE,
BEATER FOR REMOVING DUST AND DIRT FROM CARPETS OR THE LIKE,
APPLICATION FILED MAR. 13, 1919.

1,343,895.

Patented June 22, 1920.

Inventor
George H. Backmire
By W. H. Williamson
Atty.

UNITED STATES PATENT OFFICE.

GEORGE H. BACKMIRE, OF COLLEGEVILLE, PENNSYLVANIA.

BEATER FOR REMOVING DUST AND DIRT FROM CARPETS OR THE LIKE.

1,343,895.

Specification of Letters Patent. Patented June 22, 1920.

Application filed March 13, 1919. Serial No. 282,426.

To all whom it may concern:

Be it known that I, GEORGE H. BACKMIRE, a citizen of the United States, residing at Collegeville, in the county of Montgomery and State of Pennsylvania, have invented new and useful Improvements in Beaters for Removing Dust and Dirt from Carpets or the like, of which the following is a specification.

10 My invention relates to a new and useful improvement in beaters for removing dust and dirt from carpets or the like, and has for its object to provide an exceedingly simple and effective device of this description, in which the striker is composed of a series of coils working from a general center producing a cup shape.

20 A further object of my invention is to give the shank a spring action while at the same time bracing it whereby a sweeping blow may be struck and a reaction may be had which facilitates the use of the device and tends to cut the dirt and dust out of the carpet or other fabric being beaten.

25 With these ends in view, this invention consists in the details of construction and combination of elements hereinafter set forth and then specifically designated by the claims.

30 In order that those skilled in the art to which this invention appertains may understand how to make and use the same, I will describe its construction in detail referring by numerals to the drawing forming a part of this application, in which:

35 Figure 1, is a side view of my improved beater, and

Fig. 2, is a plan view thereof.

In carrying out my invention as here embodied, 1, 2, 3, 4 and 5 represent the coils of the beating member, the wire from the coils 1 and 5 being twisted together to form the handle member 6 upon the outer end of which is secured the hand hold 7.

45 The coils of the beating member vary in diameter and are so situated relative to each other that they come together upon the inner side of the beater as clearly shown while they normally stand at a slight distance from each other at the opposite side of the coils forming the general shape of a cup. The object of this arrangement is that when a beating member is swung into violent contact with the carpet or other fabric being treated the coils 2, 3, 4 and 5 will spring 50 downward under the impact and in their

reaction tend to draw the carpet in the underside of the cup. This combined action and reaction will greatly facilitate the cleaning of the carpet forcing the dust therefrom. 60 In order that the handle 6 may have ample spring action and yet not be liable to be bent or destroyed in the operation of the device, I utilize a brace wire 8 which is secured to the handle at one end as indicated at 9 and 65 at the other end as indicated at 10, a coil 11 being formed in the brace wire.

From the foregoing description it will be seen that a long sweep of the beater can be had from the fact that the handle and its 70 brace wire will spring to a considerable degree, thus adding additional movement to the movement of the hand of the operator thereby effecting a more violent blow and this blow will be utilized to the greatest extent 75 for the extraction of the dust from the carpet by the peculiar arrangement of the coils of the beating member.

Of course I do not wish to be limited to the exact form of the brace wire nor the coil 80 therein as it is obvious that this wire and its coil may be changed as for instance the coil might stand horizontal or at right angles to the position shown in the drawing and other such class of changes might be made within 85 the limits of the appended claims without departing from the spirit of my invention.

Having thus fully described my invention what I claim as new and useful is—

1. In a beater of the character described 90 the combination of a handle member, a brace wire having a spring coiled therein and having its ends attached to the handle member, a series of coils of different diameters contacting at one point and normally standing 95 at an angle to each other to produce a collapsible cup shaped beating member and a hand hold attached to the outer end of the handle member.

2. In a beater of the character described, 100 a beating member consisting of a number of coils of wire lessening in diameter from the bottom coil to the top coil, each coil being eccentric to the remaining coils, said coils contacting on one side while diverging from 105 the contact point outward so as to have a collapsing action when the beating member is forced into violent contact with a surface and then having a sudden reaction.

In testimony whereof, I have hereunto 110 affixed my signature.

GEORGE H. BACKMIRE.
